UNITED STATES PATENT OFFICE

PAUL BUHRLE, OF BRONX, NEW YORK, ASSIGNOR TO UNITED METAL GOODS MFG. CO. INC., OF BROOKLYN, NEW YORK

DESIGN FOR A CLOCK CASE

Application filed November 10, 1932. Serial No. 45,867. Term of patent 7 years.

To all whom it may concern:

Be it known that I, PAUL BUHRLE, a citizen of the United States, residing at Bronx, in the county of Bronx and State of New York, have invented a new, original, and ornamental Design for a Clock Case, of which the following is a specification, reference being had to the accompanying drawing, forming part thereof.

Fig. 1 is a front elevational view of a clock case, showing my new design.

Fig. 2 is a top plan view of the same.

The rear of the clock case is substantially flat and unornamented.

I claim:

The ornamental design for a clock case, as shown and described.

PAUL BUHRLE.
